(57) **CLAIM**

The ornamental design for a housing unit for a security and surveillance apparatus, as shown and described.

DESCRIPTION

FIG. 1 is a top and front perspective view of a housing unit for a security and surveillance apparatus, shown with surface mounted hatch plates removed to show structural detail;

FIG. 2 is a front elevation view thereof;

FIG. 3 is a left side elevation view thereof, the right side being a mirror image;

FIG. 4 is a top plan view thereof;

FIG. 5 is a bottom plan view thereof;

FIG. 6 is a back elevation view thereof;

FIG. 7 is a top and front perspective view of a housing unit for a security and surveillance apparatus, shown with surface mounted hatch plates installed;

FIG. 8 is a front elevation view thereof;

FIG. 9 is a left side elevation view thereof, the right side being a mirror image;

FIG. 10 is a top plan view thereof;

FIG. 11 is a bottom plan view thereof; and,

FIG. 12 is a back elevation view thereof.

The broken lines depict portions of a housing unit for a security and surveillance apparatus in which the design is embodied that form no part of the claimed design.

1 Claim, 10 Drawing Sheets
